(57) **CLAIM**

The ornamental design for a garment steamer, as shown and described.

DESCRIPTION

FIG. 1 is a front, left and bottom perspective view of a garment steamer showing my new design;
FIG. 2 is a rear, right and top perspective view thereof;
FIG. 3 is a front view thereof;
FIG. 4 is a rear view thereof;
FIG. 5 is a left view thereof;
FIG. 6 is a right view thereof;
FIG. 7 is a top view thereof;
FIG. 8 is a bottom view thereof; and,
FIG. 9 a perspective view of the garment steamer shown in an alternate configuration of use.
The broken lines depict portions of the garment steamer and form no part of the claimed design.

1 Claim, 9 Drawing Sheets
